UNITED STATES PATENT OFFICE.

HENRY J. GUTH, OF GOLDEN, COLORADO.

MOUNTING FOR CRYSTAL DETECTORS.

Application filed March 5, 1926. Serial No. 92,411.

This invention relates to a mounting for the crystal detector unit in radio receiving sets, and has for its principal object the provision of a device of this character which 5 will give an unusually delicate, uniform contact pressure upon the crystal.

Another object of the invention is to provide means for supporting the cat whisker so that it can have a universal movement 10 over the face of the crystal.

A further object is to provide means whereby the crystal may be readily removed from its cup.

A still further object resides in the novel 15 means for attaching the cat whisker to its supporting bar, whereby the use of set screws, solder and like is eliminated.

Other objects and advantages reside in the detail construction of the invention, 20 which is designed for simplicity, economy, and efficiency. These will become more apparent from the following description.

In the following detailed description of the invention, reference is had to the accompanying drawing, which forms a part hereof. Like numerals refer to like parts in all 25 views of the drawing and throughout the description.

In the drawing:

30 Fig. 1 is an elevation of the novel detector unit in place on an instrument panel.

Fig. 2 is a plan view of the same.

Fig. 3 is a detail vertical section through the crystal cup, taken on the line 2—2, 35 Fig. 1.

Fig. 4 is a detail view of the adjustment bar illustrating the method of attaching the cat whisker thereto.

On the drawing, a section of the instrument panel of a radio set is illustrated at 10, upon which, the novel detector unit is mounted. The unit comprises a crystal cup 11, supported on a bolt 12 which passes through, and is locked to, the instrument 40 panel 10 by means of nuts 13 and 14. Secured in the crystal cup, by means of the usual set screws 15, is a crystal 16, upon which a cat whisker 17 bears.

The position of the cat whisker 17 upon 50 the crystal is adjusted by an adjusting bar 18, terminating in an insulated finger grip 19. The adjusting bar is flattened along its mid-portion, as shown at 20, the flattened portion being provided with a longitudinal slot 21. The adjusting bar 18 rests upon a stud 22 carrying a pin 23 arranged to pass

through the slot 21. The stud 22 is secured to the instrument panel 10 by means of suitable nuts 24 and 25.

It will be noted that the extremity of the bar 18 toward the cat whisker is longer than the opposite extremity thus allowing gravity to act to press the cat whisker against the crystal. The contact between the bar 18 and the stud 22 is also accomplished by 60 gravity, there being no springs or clamps employed. By this arrangement, a very uniform and very delicate contact can be made between the crystal and the cat whisker, and, since the sensibility of a crystal detector depends upon the delicacy of this contact, the advantages of the mounting will be at once apparent. The cat whisker can be easily placed upon any part of the crystal, since it is free to swing about the pin 23 and also free to move across the stud 22. It is very desirable that the cat whisker extend vertically from the surface of the crystal and not at an angle thereto. In the 65 present device, this is accomplished by the flattened portion 20 of the adjusting bar. The cat whisker extends vertically to the surface of the flattened portion 20 and, since this surface always lies parallel to the horizontal axis of the stud 22, the cat whisker 70 will always be maintained in a vertical position.

For attaching the cat whisker to the adjusting bar, a hole 26 is provided through the latter, near its extremity. Immediately 75 adjacent to the hole 26 are two oppositely placed slots 27. The cat whisker is brought upwardly through the hole 26 and wrapped into the slots 27 until it becomes wedged 80 therein, thus forming a perfect electrical 85 and mechanical contact.

It is often very difficult to remove a mounted crystal from its crystal cup, it being necessary at times to invert the entire receiving set in order that the crystal will 90 drop from its cup. To obviate this, I place a raised bottom 28 in the crystal cup and an opening 29 in its side. This construction allows the crystal to be readily lifted from its cup by means of a common pin 30, which is inserted in the opening 29 so as to exert an upward prying action upon the crystal, 95 as illustrated in Fig. 3.

While a specific form of the improvement has been described and illustrated herein, it is desired to be understood that the same may be varied, within the scope of the 100 105 110

appended claim without departing from the spirit of the invention.

Having thus described the invention, what I claim and desire secured by Letters Patent is:

A crystal detector comprising a crystal cup adapted to support a crystal; a horizontal bar adjacent said crystal cup; a vertical pin projecting upwardly from said bar;

an arm arranged to rest on said bar and be maintained by gravity alone, said arm having a longitudinal slot for the reception of said pin; and a cat whisker extending from said arm and adapted to rest on said crystal so as to support one extremity of said bar. In testimony whereof, I affix my signature.

HENRY J. GUTH.
